UNITED STATES PATENT OFFICE.

GEORGE E. KERNES, OF OMAHA, NEBRASKA.

CARRIER MECHANISM.

Application filed October 29, 1923. Serial No. 671,313.

To all whom it may concern:

Be it known that I, GEORGE E. KERNES, a citizen of the United States, residing at Omaha, in the county of Douglas and State 5 of Nebraska, have invented certain new and useful Improvements in Carrier Mechanism, of which the following is a specification.

This invention relates to carrier mechanism, useful for moving loose earth, coal or other material, and particularly of advantage for filling ditches, and has for its object to provide parts so constructed and arranged that large volumes of earth or other 15 material may be moved quickly and conveniently by a single operator, and that stresses incident to the use of these parts will be sustained to advantage, said parts to be few and simple in order that durability 20 may be attained and manufacture will be economical.

The invention is illustrated as a "back-filler" for ditches, and includes a motor vehicle adapted to be moved from time to time as the work progresses, said vehicle being provided with all of the mechanism required, such as a boom or derrick adapted to be extended to overhang the ditch and earth to be moved, a scraper or shovel provided 30 with cables and an arrangement of drums under control of the operator for moving the shovel. The invention also includes means for supporting the derrick at selected degrees of inclination and discloses bearings 35 for certain shafts tending to materially reduce friction and arranged to be housed from the weather or other exposure. Other features considered to be new and useful will be hereinafter explained in detail.

40 In the accompanying drawing, Fig. 1 is a plan view illustrating the carrier mechanism. Fig. 2 is an end view showing the same arranged for filling a ditch. Fig. 3 is a view showing the drums and clutches in longitudinal section, the operating shaft and bearings therefor being shown in plan. Fig. 4 is a side view of parts shown in Fig. 3, being a section through a housing and bracket on line 4—4 of Fig. 3. Fig. 5 is a 45 side view of the vehicle frame and operating parts thereon, the derrick being omitted. Fig. 6 is an end view of a drum showing a brake-shoe and its supporting arm. Fig. 7 is a perspective view of the scraper or shovel. Fig. 8 is a detail illustrating means 50 for supporting a derrick. Fig. 9 is a plan

view showing means for the adjustment of a pair of extension-bars for the derrick.

Referring now to the drawing for a more particular description, the invention is 60 shown and described in connection with the front and rear axles 1 and 2, and the frame 3 of a motor vehicle.

Numeral 4 indicates a container for oil, having the form, approximately of a Maltese cross, provided with a bracket 5 for a mounting upon member 3, a second receptacle 6 being adapted to contain oil and having a bracket 7 for a mounting on said member 3, said receptacles operating to resist 70 an end thrust of an operating shaft 9, and being provided with pockets *a* in which are seated rollers 8 for bearings of said shaft.

Numeral 10 indicates a worm shaft having bearings upon rollers 11 which are seated in pockets *b* of the container 4, said worm shaft being rotatable by any suitable means, the means herein shown being the miter gear wheel 12 in engagement with a similar wheel 13 rotated by the transmission shaft 14 of 80 the engine of the motor vehicle, the operating shaft 9 being provided with a gear wheel 15 in engagement with the worm of said shaft 10 to cause its rotation. Numeral 16 indicates a cap adapted to be secured to 85 the container 4, and a cap 17 is provided for the container 6.

At 18 and 19 are indicated a pair of drums mounted as idlers upon the shaft 9, and adapted to be rotated by said shaft when engaged by clutches, the clutch for the drum 18 being indicated at 20, and the clutch for the drum 19 being indicated at 21, said clutches being splined upon the shaft, as best shown in Fig. 3.

90 Numerals 22 and 23 indicate a pair of hand levers for a control of the clutches, said levers being adapted to have swinging movements while mounted upon a bracket 24. A link 25 of angular form is employed 100 for a control of the sliding movements of the clutch 20 by use of lever 22, and a link 26 is connected with the clutch 21 and the hand lever 23 for a control of said clutch 21.

105 Numerals 27 and 28 indicate a pair of brake shoes, each being adapted to be moved into engagement or disengagement with a drum, the shoe 27 being provided with an arm 29 which is mounted upon the link 25, and the shoe 28 being provided with an arm 30 which is mounted upon the link 26, and 110 it will be understood that a movement of a

hand lever 22 or 23 in one direction may move a clutch into engagement with a drum to cause a revoluble movement thereof, the brake shoe being automatically released from said drum, a movement of a lever in an opposite direction causing a release of the clutch from the drum and, automatically, causing engagement of the brake-shoe with said drum, the function of terminating 10 the rotation of a drum, or either of them, by operation of a brake-shoe, being a matter of advantage and quite necessary when moving earth into trenches, ditches or other depressions.

15 Numeral 31 indicates a container for carrying a load, and shown as a scoop or shovel adapted to move the earth for filling a ditch 32. A derrick is pivotally mounted on the vehicle as indicated at *h* for supporting the shovel, said derrick preferably consisting of 20 a pair of outwarwdly convergent, tubular holder-arms 33 having extensible or telescoping arms 34 mounted therein. Numeral 35 indicates a cable which is mounted 25 on the drum 18 and is connected with the front end of the shovel, and numeral 36 indicates a cable which is connected with the rear end of the shovel, said cable being in engagement with a sheave 37 supported by 30 the arms 34 and mounted on the drum 19.

Numeral 38 indicates a frame approximately of inverted V-shaped which is mounted on the vehicle for supporting the derrick and its extension-arms 34 while disposed at selected degrees of inclination, a strand 39 being wound upon or otherwise secured to a drum 40 which is provided for said frame 38, said strand being also secured to a bar *c* (Fig. 8.) which connects the extension-arms 34, said drum preferably being provided with a crank 41 for its rotation when adjusting the derrick to a selected degree of inclination, a pawl 42 being adapted to engage a toothed sector 43, which is provided for said frame.

50 Any suitable connection for the outer ends of arms 34 may be provided which will permit said arms to be moved inwardly or outwardly from the tubular arms 33, and for this purpose I have shown bars *c* with nuts *d* threaded thereon, said bars being mounted in the arms 34, and it is obvious that the outer ends of said arms may be disposed somewhat further apart, while connected by the bars *c*, to permit said arms 34 to be moved inwardly of the tubular arms 33.

60 It will be appreciated that the operating shaft 9, on account of stresses directed thereto, should be firmly supported, and that its bearings should be protected from the presence of loose earth or dust, and it is believed that the construction as shown and described provides these features.

65 It will be noted that a single operator is all that will be required for the work. To

move the shovel to permit it to be loaded, an operator moves the hand-lever 23 in one direction to cause the clutch 21 to engage the drum 19 and causing a release of the brake-shoe 28 from said drum, the cable 36 70 being wound upon said drum 19 and operating to move the shovel rearwardly to a loading position, at which time the operator moves said hand-lever 23 in an opposite direction, which removes the clutch 21 from 75 said drum 19 and causes a pressure of the brake-shoe 28 upon the end of said drum for preventing a further rotation thereof.

The operator then causes a movement of 80 the shovel toward the ditch by use of the hand-lever 22, a movement of said lever in one direction causing the clutch 20 to engage the drum 18 and causing a release of the brake-shoe 27 from said drum, the rotation of the drum 18 causing the shovel to 85 be drawn toward the ditch and to be filled during this movement. As soon as the shovel reaches the ditch the operator moves the hand-lever 22 in a direction opposite to that last mentioned, which of course, releases the clutch 20 from said drum 18, the brake-shoe 27 preventing any additional rotation of said drum since it will be automatically pressed against the end of the drum.

90 The sides of the shovel at its open end are provided with apertures *e* so that the hooks *f* of the pair of strands *g*, which are provided, may engage in said apertures. These apertures *e* are disposed at varying 100 distances from the bottom of the shovel to permit adjustments to be made and providing a mounting for the hooks somewhat further from the bottom and tending to cause the front end or blade of the shovel 105 to enter the ground readily when drawn toward the ditch, and being of advantage in instances where the ground is hard or has been packed. Numeral 38' indicates a 110 tilting-block or heel for the shovel, this being of advantage and quite necessary to operation since it dispenses with manual control and operates to maintain the shovel in an inclined position when drawn toward a ditch.

115 The angular arms 29 and 30 for the respective links 25 and 26 are provided with prongs *h'*, as best shown in Fig. 6, said prongs being suitably secured to the brake-shoes. End thrusts of drums 18 and 19 are prevented by collars *x* which are secured to the shaft 9.

120 While I have shown the tubular arms of the derrick to be mounted upon the axles, they may of course, be mounted upon other parts of the vehicle if desired, and while I have shown the operating parts and derrick at the left or "near side" of the vehicle, they would be equally operative, of course, if located at either side of the vehicle, and it will be understood that changes in form,

size, proportion of parts and minor details may be made, as found to be of advantage, said changes being within the scope of the invention as claimed.

5 I claim as my invention,—

1. In carrier mechanism, a rotatable shaft, a brake-shoe, a clutch keyed on the shaft, a link loosely engaging the clutch and having an arm secured to the brake-shoe, a drum journalled on the shaft intermediate the clutch and brake-shoe, said link being movable in one direction to cause coincident engagement of the clutch with and disengagement of the brake-shoe from the drum, and being movable in an opposite direction to cause coincident disengagement of the clutch from and engagement of the brake-shoe with said drum.

2. In carrier mechanism, a rotatable shaft provided with a collar, a brake-shoe journalled on the shaft, a clutch keyed on the shaft, a link loosely engaging the clutch and having an arm secured to the brake-shoe, and a drum journalled on the shaft in engagement with the collar and disposed between the clutch and brake-shoe, said link being movable in one direction to cause coincident engagement of the clutch with and disengagement of the brake-shoe from the drum, and being movable in an opposite direction to cause coincident disengagement of the clutch from and engagement of the brake-shoe with said drum.

In testimony whereof, I have affixed my signature.

GEORGE E. KERNES.
